No. 868,854.

PATENTED OCT. 22, 1907

J. L. FIRM.

ASSOCIATING, FOLDING, AND DELIVERING MECHANISM FOR PRINTING MACHINES.

APPLICATION FILED JAN. 25, 1907.

UNITED STATES PATENT OFFICE.

JOSEPH L. FIRM, OF BERWYN, ILLINOIS, ASSIGNOR TO THE GOSS PRINTING-PRESS COMPANY.
OF CHICAGO, ILLINOIS.

ASSOCIATING, FOLDING, AND DELIVERING MECHANISM FOR PRINTING-MACHINES.

No. 868,854.

Specification of Letters Patent.

Patented Oct. 22, 1907.

Application filed January 26, 1907. Serial No. 354,101.

To all whom it may concern:

Be it known that I, JOSEPH L. FIRM, a citizen of the United States, residing at Berwyn, in the county of Cook and State of Illinois, have invented new and useful Improvements in Associating, Folding, and Delivering Mechanism for Printing-Machines, of which the following is a specification.

This invention relates to an assembling, folding and delivery mechanism for printing machines of the web perfecting type, and its object is to provide an improved, compact and simple mechanism for associating, cutting, and transversely folding a plurality of webs from a plurality of longitudinal formers or folders.

A further object of the invention is to provide such means allowing optional or different associations of the different webs to produce different products.

A further object of the invention is to provide a rotary folding and cutting mechanism having a double action at each rotation, whereby its speed is increased accordingly, as compared with a cutter and folder which acts on only one product at each rotation.

The accompanying drawing is a diagrammatic front elevation illustrating the invention.

The drawings show three pairs of longitudinal folders or formers, to which two superposed webs are carried from the printing mechanisms. These webs are or may be four pages wide, so that the webs, when slitted, will amount to twelve webs two pages wide; but the apparatus is capable of use with webs of other sizes or widths, and is not limited in its use to the number or kind of webs herein particularly referred to. The longitudinal folders of each pair are shown side by side, but they may be set at right angles to each other or facing each other, if desired, provided their products are led to the folder and cutter hereinafter described.

Referring specifically to the drawing, the longitudinal folders comprise three pairs, A and A', B and B', and C and C'. The first pair is provided with a roller 1, the second pair with a roller 1', and the third pair with a roller 1'; likewise each pair has a set of grip wheels 2, 3, 4 and 5, 2', 3', 4' and 5', and 2'', 3'', 4'' and 5''. The three sets of upper and lower four-page wide webs pass respectively between the rollers and the gripping wheels and are slitted by the respective slitters 6, 6' and 6'' into six sets of webs, one set for each folder, and these webs will hereafter be individually referred to.

The webs G and H pass down the longitudinal folder A, and the webs K and L down the longitudinal folder C, and the webs M and N down the longitudinal folder C'. The first two pass between the rollers 7 and 8 and reach the other sets at the roller 9, said other sets passing respectively between the rollers 115 and 116, and 117 and 118, and over the rollers 120 and 119, all the

webs being thus associated at the carrier or rotary 55 cutter cylinder F.

From the roller 9 the webs pass to the female cutting cylinder D where they are impaled on the pins 10 of the carrier F and are then cut by the knife 11 co-acting with a matrix 12 in the female cutting cylinder D. Then 60 they pass around with the carrier and the transverse folding blade 21, acting radially at the opening 18, thrusts the fold between the rollers 19 and 20 and thence between the tapes 22 and 23. These tapes pass over and under the guide rollers 19, 20, 24, 25, 26, 27 and 28, 65 in the manner shown in the drawing, and deliver the product to the rotary fly 29 which drops the same on the apron 30 moving over the rollers 31 and 32. This disposes of the product of the six webs mentioned. Simultaneously, the other webs are acted on as follows: the 70 webs I, J pass down the folder A', the webs O, P down the folder B, and the webs Q, R down the folder B', passing respectively between the rollers 13 and 14, 108 and 109, and 105 and 106, and under rollers 107 and 121, to association between rollers 110 and 111, after which 75 the associated webs pass under roller 112, between rollers 113 and 114 and thence between the female cutting cylinder E and roller E' and are impaled by the pins 33 on the carrier F, and are cut by the knife 34 co-acting with the matrix 12' in the female cutting cylinder E, 80 these parts being located diametrically opposite to the similar devices which act upon the other webs as hereinbefore described. From the cylinder E the webs now being considered pass with the carrier and the folding blade 38 acting at the opening 37 thrusts the paper between the rollers 35 and 36 whence they pass between the tapes 39 and 40. These tapes pass around rollers 35, 36, 85 41, 42, 43, 44 and 45, and deliver the product to the rotary fly 46 by which the papers are dropped on the apron 47 moving over the rollers 48 and 49, this delivery being 90 on the opposite side of the folder to the delivery formerly described. It will be seen that on each half revolution of the carrier F the folding blades 21 and 38 thrust a folded paper between the rollers 19 and 20, and 35 and 36, to the opposite delivery devices, respectively. The pins 10 and 33 release the forward ends of the webs at the time the papers are thrust or transversely folded. The pins are withdrawn by rocking the levers 50 and 51 by the cams 54 and 55 of the folding blades 21 and 38, the levers being returned to position 95 100 by the springs 52 and 53.

The particular cutting and folding devices herein referred to, and the means for operating the same, will be found specifically described and illustrated in my United States Patent No. 658209, dated September 18, 105 1900, and reference is made thereto for detailed information if desired.

The use of only one carrier, delivering double or sin-

gle from six longitudinal folders, gives large capacity, and a saving of carriers and folders and floor space. It also gives an advantageous association of webs and products, and capable of more variation in the manner of association of the different webs than if separate transverse folders were used.

Various modifications may be made or will suggest themselves to those skilled in the art, without departing from the scope of the invention or the following claims.

10 I claim:

1. In a mechanism of the kind described, the combination with a rotary carrier, and double cutting and folding mechanisms co-operating therewith and located respectively on opposite sides thereof and arranged to set on different webs at each half rotation of the carrier, of means to simultaneously supply webs to the carrier at opposite sides thereof, and means to deliver the product therefrom after being cut and folded.
2. In a mechanism of the kind described, the combination with a rotary carrier, and a plurality of cutting and folding mechanisms carried thereby and co-operating therewith, of means to simultaneously supply webs separately to the several cutting mechanisms, and means to deliver said webs separately as the product, after being cut and folded, from opposite sides of the carrier.
3. In a mechanism of the kind described, the combination with a rotary carrier, of means to supply a plurality of webs thereto, means on the carrier to cut said webs separately, and means to separately fold and deliver the webs so cut.
4. In a mechanism of the kind described, the combination with a rotary carrier, of means to supply a plurality of sets of associated webs thereto, and means to cut, fold and deliver each set separately the cutting and folding means being carried by the carrier.
5. The combination of a rotary carrier having a plural-

ity of web-engaging and cutting and transverse folding mechanisms co-operating therewith, means to separately supply webs to said mechanisms respectively, and means to separately deliver the product therefrom.

6. In a mechanism of the kind described, the combination of a plurality of longitudinal folders, means to associate the webs therefrom into two sets, a rotary carrier having cutting, transverse folding and delivery mechanisms on opposite sides thereof operating simultaneously, and means to supply the sets of webs to said carrier and mechanisms respectively.

7. In a mechanism of the kind described, the combination of a plurality of longitudinal folders, a rotary carrier having cutting, transverse folding and delivery mechanisms respectively on opposite sides thereof operating simultaneously, and means to supply a web from a folder to each of said cutting, folding and delivery mechanisms.

8. The combination of a rotary carrier, cylinders at opposite sides thereof, the carrier and cylinders having co-operating knives and matrices, transverse folding blades carried by the carrier, on opposite sides thereof, and delivery rollers located at both sides of the carrier and co-operating with the folding blades.

9. The combination of a rotary carrier having web-engaging and cutting devices on opposite sides thereof, transverse-folding blades carried by the carrier on opposite sides thereof and substantially midway of the circumference of the carrier between said devices, paper feeding devices at opposite sides of the carrier, and delivery devices on opposite sides of the carrier, co-operating simultaneously with said blades.

In testimony whereof I have signed my name to this specification in the presence of two subscribing witnesses.

JOSÉPH L. FIRM.
